UNITED STATES PATENT OFFICE.

HENRY HOWARD FREER, OF LEICESTER, ENGLAND, ASSIGNOR, BY MESNE ASSIGNMENTS, TO BOSTON MACHINE WORKS COMPANY, OF LYNN, MASSACHUSETTS, A CORPORATION OF MASSACHUSETTS.

FOLDING-MACHINE.

1,161,040.

Specification of Letters Patent. Patented Nov. 23, 1915.

Application filed August 10, 1910. Serial No. 576,519.

To all whom it may concern:

Be it known that I, HENRY H. FREER, a subject of the King of England, residing at Leicester, Leicestershire, England, have invented certain Improvements in Folding-Machines, of which the following description, in connection with the accompanying drawings, is a specification, like reference characters on the drawings indicating like parts in the several figures.

This invention relates to folding or like machines, and more especially to that class of machine which is adapted to fold or both to cut or slit and to fold the edges of leather or similar sheet material.

According to this invention there is provided in a machine for folding the marginal portion of leather or other sheet material a marking device or devices (such for example as a plate on which are a series of marking points arranged to a design) to impress a design on the material, that will constitute a guide marking for a succeeding operation that is to be performed upon the material.

A stitch-line-marking operation is performed on the uppers of shoes to indicate the line of succeeding stitching and heretofore the operation has usually been performed after the edge of the material has been folded, but unless performed with very great care, an accurate stitch-line-marking has not been secured. By accomplishing the stitch-line-marking at the same time that the edge is folded while the work is held in the folding machine in the position in which it is folded, a perfectly uniform and accurate relationship of stitch-line-marking and folded edge is obtained without any chance or possibility of error, and hence there results a general improvement in the quality of the work from the use of this invention.

The impressing means may take the form of a plate having on it marking devices arranged in the required design, and conveniently the said impressing means may be removably attached to a part of the machine, as for instance the table. When a plate is used it may be made of zinc or other ductile metal, and the marking devices formed by a series of projections in the desired outline raised thereon by means of a punch.

This invention also comprises the provi-

sion, in addition to the devices which exert the required pressure for the folding operation, of separate means for engaging the slightly springy folding or other blade at a plurality of points so as to conform it to slight unevennesses in the thickness of the material to be marked. Conveniently these means are made adjustable so that they may be regulated to operate at a series of points arranged along the line of contour of each of a variety of designs; furthermore, the means may be provided with an adjustment or adjustments to vary the amount of pressure that is delivered at one or more points along the contour, for example, where the design ends in a scroll the pressure exerting means adjacent to the scroll may be made to deliver considerably more pressure to that part of the design than to those parts of the design that are composed of a less concentrated number of pricker points. These means may come into operation simultaneously with the devices which exert the folding pressure or they may come into operation after the folding operation has been completed.

A convenient embodiment of the foregoing and other features of the invention will now be described as applied to a machine well known as the Booth folding machine.

In the accompanying drawings,—Figure 1 is a plan of a Booth folding machine sufficient to illustrate the present invention; Fig. 2 is a side elevation turned into a position to agree with Fig. 1; Fig. 3 is a plan of the marking device; and Figs. 4 and 5 show the folding mechanism in different positions.

The usual type of Booth folding machine comprises a table 1 on which the work to be folded is laid, a holder 2 to hold the work in position on the table, a creaser-plate 3 to hold the work and determine the position of the crease or fold, and a folder 4 to fold the edge of the work over the creaser-plate. The holder and the creaser-plate are attached to arms 6 which are secured to a rock-shaft, and pressure is exerted to keep the holder and plate pressed against the work by means of cams each of which is connected to the corresponding arm through a system of levers and a yielding member. Thus the holder and the creaser-plate are

yieldingly pressed against the work. These features and the other parts of the machine not herein described are arranged and operated in substantially the same manner as in the usual Booth folding machine. According to the embodiment of the present invention about to be described means are provided to perform the operation of "facing marking", *i. e.* to mark a folded upper adjacent to its folded edge so as to indicate the correct line for the subsequent sewing of the upper, and to this end a plurality of rows of indentations is made on the upper at the time when the folding operation takes place. The indentations are made by providing the surface on to which the fold of the upper is pressed with a row of small protuberances arranged in a line of the shape with which it is desired to mark the upper.

A thin zinc plate 7 in the present example constitutes the means to produce the required indentations and projections 8 are formed on it by means of a punch. This plate is attached to the table of the machine in such a manner that it can be easily removed to make way for a plate having a different design when a different size or class of work is desired to be operated on, a creaser-plate 3 being changed at the same time as in the Booth folding machines.

The plate 7 is positioned on the table by dowels that are secured in the table and enter corresponding holes 9 in the plate. Two clamp members are provided one at each side of the plate and comprising an L-shaped strip 10 that is secured to the table by headed screws 12 that pass through inclined slots in the strip. A portion of each strip is turned outward at 14 to constitute a convenient means of moving the strip endwise to clamp or unclamp the plate 7.

As already explained the creaser-plate exerts pressure on the work to hold it in position, but this pressure would probably not be sufficient at all times properly to indent the material and further pressure-applying means are therefore provided. These means comprise a pair of levers 15 that are fulcrumed at 16 to the machine frame, each having at its end a crosspiece 18 adjustably secured to it by a bolt 19. Screwed into holes in either end of the crosspiece are screws 20 which are adapted to bear on the head 22 which supports the holder 2 and creaser-plate 3. The free ends of the levers 15 carry rolls 17 which are acted upon by cams 23 and thus a direct pressure is applied to the creaser-plate and consequently to the work.

The cams 23 may be so arranged that the pressure due to their action is exerted simultaneously with the yielding pressure exerted by the cams actuating the creaser-plate and

the holder as hereinbefore described or they may be arranged to act after the folding operation is completed.

The arms 25 of the levers 15 which contact with the head 22 are made adjustable. Each arm 25 is formed as a sleeve in which slides a rod 27 which is longitudinally grooved. In a projection 29 from the sleeve is a spring-pressed locking-pin 30 which extends into the groove and so prevents the rod from turning and engages teeth 32 formed at the bottom of the groove in the rod and so prevents endwise movement of the rod. By this construction when varying contours of design are interchanged in the machine the arms can be adjusted to correspond and the crosspieces on the end of these arms may be swiveled and adjusted lengthwise on the bolt 19 to bring the impressing screws 20 into the best working relationship with the design.

Although the design-carrying plate is described as attached to the table of the machine it is immaterial to what part the plate is attached provided it is properly located to mark the stock in the desired manner.

Having described my invention, what I claim as new and desire to secure by Letters Patent of the United States is:—

1. A folding machine having, in combination, a design forming member, mechanism for causing said member to be pressed against the work, additional means for increasing the pressure upon said member, and a lock for holding said last named means in different adjusted positions to vary the location of the area over which the additional pressure is exerted.

2. In a machine of the class described, mechanism to fold the edge portion of work and to form a design thereon in combination with auxiliary pressure applying means comprising a lever, a sleeve on said lever, a rod adjustably held in said sleeve and arranged to apply pressure on the design forming mechanism, and means for actuating said lever.

3. A machine of the class described having, in combination, a support for the work provided with a raised design, a clamp for holding the work in place, a creaser and a folder for making the fold, means for operating said clamp, creaser and folder, and additional means for pressing the work against the design during the folding operation.

In testimony whereof I have signed my name to this specification in the presence of two subscribing witnesses.

HENRY HOWARD FREER.
